US00D425201S

United States Patent [19]

Tetzlaff et al.

[11] **Patent Number:** Des. 425,201[45] **Date of Patent:** ** May 16, 2000[54] **DISPOSABLE ELECTRODE ASSEMBLY**

[75] Inventors: **Philip Mark Tetzlaff**, Golden; **Dale Francis Schmaltz**, Fort Collins; **Steven Paul Buysse**, Longmont; **Kate Ryland Lawes**, Boulder, all of Colo.

[73] Assignee: **Sherwood Services AG**, Schaffhausen, Switzerland

[**] Term: **14 Years**

[21] Appl. No.: **29/095,493**

[22] Filed: **Oct. 23, 1998**

[51] **LOC (7) Cl.** **24-02**

[52] **U.S. Cl.** **D24/144**

[58] **Field of Search** D24/143, 144, D24/148; 606/40, 41, 45, 51, 52, 50, 205-208

Primary Examiner—Eric Watterson[57] **CLAIM**

We claim the ornamental design for a disposable electrode, as shown.

DESCRIPTION

FIG. 1 is a perspective view of a disposable electrode showing our new design;

FIG. 2 is a left side view of the disposable electrode;

FIG. 3 is a rear view of the disposable electrode;

FIG. 4 is a right side view of the disposable electrode;

FIG. 5 is a front view of the disposable electrode;

FIG. 6 is a bottom view of the disposable electrode; and,

FIG. 7 is a top view of the disposable electrode.

The end portion shown broken away for ease of illustration.
